TELEGRAPH SENDING KEY

Walter Raymond Starkins, Rochester, N. Y.

Application March 7, 1940, Serial No. 322,780

10 Claims. (CL. 178—82)

This invention relates to a key or device for sending telegraphic signals, either over land telegraph lines, cables, or wireless (radio) transmitters.

5 An object of the invention is the provision of an improved and simplified sending device, of simple and sturdy construction, so designed as to reduce to a minimum the effort required of the operator, and eliminate or greatly reduce 10 the fatigue to which operators have heretofore been subjected.

Another object is the provision of a sending key which can be adjusted to operate at any desired speed within wide limits, and in which 15 the adjustment can be changed while the key is in operation, without interfering with the progress of sending a message.

Still another object is the provision of a sending key so designed as to determine mechanically 20 the lengths of dashes to be sent as well as dots.

A further object is the provision of a key for sending dots of mechanically determined length and dashes of mechanically determined length in 25 any combination desired by the operator, the spacing between the dots and dashes being manually controlled by the operator while the lengths of the dots and dashes themselves are mechanically controlled so as to be of accurate predetermined length.

To these and other ends the invention resides in certain improvements and combinations of parts, all as will be hereinafter more fully described, the novel features being pointed out in 35 the claims at the end of the specification.

In the drawings:

Fig. 1 is a front elevation of a device constructed in accordance with a preferred embodiment of the invention;

40 Fig. 2 is an end view thereof, viewed from the right hand end of Fig. 1;

Fig. 3 is a horizontal section taken substantially on the line 3—3 of Fig. 2;

45 Fig. 4 is a top plan view thereof;

Fig. 5 is a view similar to a fragment of Fig. 1, with parts broken away and parts in vertical section, showing the latch of the dot sending disk released so that this disk may rotate to send one or more dots;

50 Fig. 6 is a side elevation of the dash sending disk and associated parts, and

Fig. 7 is an elevation illustrating a modified form of circuit closing switch controlled by the 55 dot and dash disks.

The same reference numerals throughout the several views indicate the same parts.

It is well known that the operation of ordinary telegraph sending keys, of the type in which a separate movement of the operator's fingers must take place for each dot and for each dash, involves considerable nervous strain and energy on the part of the operator, with resultant fatigue. Efforts to remedy this have been made by the provision of devices for automatically sending some of the signals, the construction probably most commonly used being one in which a plurality of successive dots may be sent by a single movement of the operator's fingers, but in which separate movements of the operator's fingers are required for sending separate dashes, so that there is still a considerable amount of energy required, with resultant fatigue.

As distinguished from such prior constructions, the present construction provides a simplified 20 and more efficient device, capable of sending any number of successive dashes as well as any number of successive dots without requiring separate movements by the operator for each dash or each dot. The length of each dash and spacing between successive dashes, as well as the length of each dot and spacing between successive dots, is mechanically controlled and regulated by the present device, the speed of operation of which is readily adjustable.

30 The device in the preferred form shown as an illustrative embodiment in the accompanying drawings, comprises suitable frame parts of metal or other desirable material, serving to support a suitable motor 11 constantly driving a 25 shaft 13. The motor 11 may conveniently be a small electric motor of constant speed, although a spring motor may be employed if desired.

35 Fixed to the shaft 13 to rotate constantly therewith is a worm 15 driving a worm gear 17 fixed to a hub 19 freely rotatable on a vertical fixed shaft 21 mounted on a bracket 23 of the frame. At the lower end of the hub 19 is a horizontal disk 25 the lower face of which has firmly secured thereto a layer of any suitable friction material 27.

40 A coiled spring 29 surrounding the shaft 21 between the upper end of the hub 19 and the lower side of the bracket 23, constantly tends to press the hub 19, the gear 17, and the disk 25 45 downwardly to hold the friction material 27 on the disk firmly against the periphery of a second disk 31 mounted for longitudinal sliding movement on the shaft 33 which is journaled in the frame of the machine. The frictional en- 50 55

gagement between disks 25 and 31 causes the rotation of the disk 25 to drive the disk 31 at a speed ratio relative to the disk 25 which depends on the position of the disk 31 with respect to the 5 axis of the shaft 21. As the disk 31 is brought closer to the axis of the shaft 21, the ratio of its speed to the speed of the disk 25 is decreased, and conversely the disk 31 turns at a maximum speed when it is in contact with the disk 25 close 10 to the periphery of the latter.

The disk 31 is fixed to a hub 35, likewise slideable longitudinally on the shaft 33, which hub 35 is provided with a longitudinally arranged series of teeth each extending circumferentially around 15 the hub, as shown. These teeth mesh with the teeth of a pinion 37 fixed to a shaft 39 journaled in the frame and provided with a knob 41 at its forward end. By turning the knob 41 in one direction or the other, the sleeve 35 is moved 20 backward or forward along the shaft 33 to adjust the position of the driven disk 31 on the face of the driving disk 25, thus changing the speed transmission ratio.

Fixed to the shaft 33 is a collar 45 to which a 25 pin 47 is fixed, this pin extending leftwardly from the collar in a direction parallel to the shaft 33, and passing loosely through a hole in the disk 31. Rotation of the disk 31 is thus transmitted through the pin 47 to the shaft 33. Instead of 30 using this pin arrangement, the hub 35 of the disk 31 could be slidably keyed to the shaft 33, or the shaft could be made of square or other non-circular shape, with the opening through 35 the hub of corresponding shape to provide a non-rotatable connection between the shaft and the hub 35, while permitting longitudinal sliding movements.

Fixed to the shaft 33, to the right of the collar 45, is a collar 51, the right hand face of which 40 is provided with friction material 53. Still farther to the right, a collar 55 is loose on the shaft 33 and has its left hand face provided with friction material 57. Between these two collars and contacting with both of the friction coatings 45 53 and 57, is a dash-sending disk 61 loosely mounted on the shaft 33 for free rotation thereon, except as such rotation is impeded by contact with the friction surfaces. A coiled spring 63 surrounding the shaft 33 to the right of the collar 50 55, reacts rightwardly against a collar 65 fixed to the shaft and constantly presses leftwardly against the collar 55, to keep this collar in contact with the disk 61 and to keep the disk 61 in contact with the friction coating 53 on the collar 55. A pin 67 fixed to the collar 65 extends leftwardly into a hole in the collar 55, to establish 55 a driving connection between the collars 65 and 55, while permitting slight axial movement of the latter. With this arrangement, whenever the 60 disk 61 is not otherwise restrained, it will turn with the shaft 33, because of its contact with the friction material 53 and 57. But if the disk 61 is forcibly restrained, it will remain stationary, the shaft 33 and collars 51 and 55 continuing 65 their uninterrupted rotation.

Still farther to the right, on the same shaft 33, is a similar arrangement but with the parts placed in reversed order. These parts include a collar 71 fixed to the shaft 33 and corresponding 70 in general to the collar 51, provided with a friction surface 73 on its left face, and another collar 75 provided with friction material 77 on its right face. Between the two collars is a dot sending disk 81, while a coiled spring 83, reacting against a collar 85, tends to clamp the disk 81 between

the friction surfaces 73 and 77, so that this disk 81 like the disk 61, tends to turn with the shaft 33, but can be forcibly restrained from turning. A pin 87 on collar 85 enters a hole in collar 75.

The periphery of the dash sending disk 61 is 5 provided with teeth which are relatively long in a circumferential direction, as seen in Fig. 6, with relatively short cut-away spaces between adjacent teeth. The dot sending disk 81 is provided with teeth which are relatively short in a circumferential direction and with relatively long cut-away spaces between adjacent teeth as seen in Fig. 2. The telegraph or radio circuit is controlled by these teeth. For instance, immediately behind the dash disk 61 there may be an 15 upstanding strip of resilient metal 91 (Fig. 6) insulated from the frame of the machine by suitable insulation 93, the upper end of the strip being bent forwardly so as to lie against the teeth of the disk 61 as this disk is rotated, or to 20 enter the cut-out space between the teeth when the disk stops in proper predetermined position as seen in Fig. 6. Similarly, behind the dot disk 81 is an upstanding resilient metal piece 95, like- 25 wise mounted on the insulating block 93 and hav- 30 ing its upper end bent forwardly to engage with the teeth of the disk 81 or to lie in the cut-out spaces between the teeth. The key circuit of the 35 telegraph, cable, or radio transmission system is connected at one side to the frame of the device, 30 so as to be in electrical contact with the disks 61 and 81, and connected at the other side to both of the metal feelers 91 and 95, such as by being connected to a binding post 97. So long as both disks 61 and 81 are held stationary in pre- 35 determined position (by mechanism described below) both feelers 91 and 95 extend into the cut-out spaces between the teeth of the disks and do not contact with the disks, so that the circuit is open. If either disk be rotated, its teeth will 40 make contact with the corresponding one of the feelers 91 and 95, thus closing the circuit, which will remain closed for only a short time as each tooth of the dot disk 81 passes the end of the feeler 95, or for a longer time as each tooth of 45 the dash disk 61 passes the end of the feeler 91. The number of successive dots or successive dashes to be sent will depend on the extent to which the disks 81 and 61 are permitted to rotate, before being stopped.

Where the current passing through the key circuit is large, it may be desired not to connect one side of the key circuit directly to the frame of the machine, but to keep the frame of the machine entirely out of the electric circuit. In 55 this event, instead of making the contact directly between the disks 61 or 81 and cooperating feeler members, the teeth on the disks may serve to operate a separate switch, in the manner shown in Fig. 7. Here, the insulating block 93, instead 60 of being provided with the feelers 91 and 95, is provided behind each disk with two upstanding metal members 101 and 103 having cooperating contact points 105 and 107 at their upper ends. The resilience of these members 101 and 103 65 normally holds the contact points 105 and 107 separated from each other. The member 103 carries a cam extension 109 of insulating ma- 70 terial extending into position to be deflected by the teeth of the associated sending disk as the disk rotates. When the disk is stationary the cam 109 is in the cut-out space between teeth, allowing the contact points 105 and 107 to remain open, but when the disk rotates, the teeth 75 deflect the cam portion 109, throwing the contact 75

point 107 against the contact point 105 and closing the circuit, one side of which is connected to the member 101 and the other side of which is connected to the member 103. An arrangement 5 of this kind is used in connection with each of the two disks 61 and 81, and no current flows through the frame of the machine.

For controlling the movements of the disks 61 and 81, the following mechanism is provided. On 10 the frame of the machine, a stationary shaft 121 projects forwardly. Mounted on suitable bearing sleeves on this shaft, for swinging movement independently of each other, are two stop arms, a leftwardly extending arm 123 to contact with the dash disk 61, and a rightwardly extending arm 125 to contact with the dot disk 81. When 15 one of these arms is in its lower position, it partially enters the cut away space between teeth of its associated disk and contacts with one tooth 20 in such position (as shown in Figs. 2 and 6) as to hold the disk stationary at the proper point so that the associated contact member 91 or 95 (or the cam 109, when the alternative arrangement is used) will lie in another cut away space 25 of the disk. When either of the stop arms 123 and 125 is raised slightly by swinging it upwardly on the shaft 121, it clears the tooth of its associated disk and permits this disk to rotate.

An arm 127 (Fig. 3) connected to the right 30 hand stop arm 125 extends downwardly from the shaft 121 and has a forward extension 129 provided at its forward end with an insulating finger piece 131. Stop screws 133 and 135 (Fig. 3) limit the extent of swinging movement of the 35 arms 127 and 129 in either direction.

Another arm 137, suitably connected to the left 40 hand stop arm 123, likewise extends downwardly from the shaft 121 and is provided at its lower end with a forward extension 139 having at its forward end an insulating finger piece 141. Stop screws 143 and 145 (Fig. 3) limit the swinging movement of this arm in either direction.

The arm 127 carries a leaf spring 151 (Fig. 1) reacting against a fixed part 153 of the frame 45 and resiliently tending to hold the arm 127 as far leftwardly as the stop screw 133 will permit. A similar leaf spring 155, mounted on the arm 137 and reacting against the fixed frame part 157, tends to hold the member 137 as far to the 50 right as its stop screw 145 will permit. These leaf springs normally hold the parts of the control mechanism or stop mechanism in the positions shown in Figs. 1 to 4, inclusive.

If the finger piece 131 is moved slightly to the 55 right from the position shown in Figs. 1 and 4 to the position shown in Fig. 5, this will swing the arm 127 to the right against the force of the spring 151, and will raise the stop arm 125 connected to the arm 127, thus permitting the dot disk 81 to rotate with the constantly rotating shaft 33. One or several dots will be sent, depending on how long the operator maintains the rightward pressure on the finger piece 131. As soon as he releases the finger piece, the spring 60 151 tends to restore the stop arm 125, and the arm drops into the next notch of the disk and stops rotation thereof.

Similarly, if the finger piece 141 be pressed 70 leftwardly, against the force of the spring 155, this will raise the dash stop arm 123 and permit the dash disk 61 to rotate. One or more dashes will be sent, depending on the length of time that the operator maintains the leftward pressure on the finger piece 141, and when pressure 75 is released, the stop arm will enter the next

available notch of the dash disk, stopping rotation thereof. Thus it is seen that by pressing the member 131 to the right, one or several successive dots may be sent, and by pressing the member 141 to the left, one or several successive dashes may be sent, each dot being of uniform predetermined length and each dash being of uniform predetermined length, which lengths can be varied by turning the knob 41, while the device is in operation and without interfering with 10 the sending of a message, to vary the speed at which the shaft 33 rotates. Since the operator need make only one motion to send several dots or one motion to send several dashes, it is seen that the physical work of the operator is greatly 15 reduced, and consequent fatigue is largely eliminated.

To prevent the accidental movement of both 20 finger pieces 131 and 141 at the same time, which would result in scrambling the dots and dashes, 25 a stop screw 161 (Fig. 4) is mounted on the lever 139 and extends toward the lever 129, leaving such clearance between the levers that only one 30 can be moved to its releasing position at a time. Whenever the lever 129 is moved sufficiently far 35 to release its associated disk, the stop screw 161 prevents the other lever 139 from being so moved, and vice versa.

If the circuit connections are such that one 30 side of the key circuit is connected to the frame 35 of the machine, then to insure proper carriage of the current from the frame to the dot and dash disks, it may be advisable to mount on the frame a pair of leaf springs 171 and 181 (Fig. 1) the former pressing lightly against one side of the 35 disk 61 and the latter pressing lightly against one side of the disk 81, to form electrical connections therewith. These springs can be eliminated if the circuit closing arrangement shown in Fig. 7 is employed, where no current passes 40 through the frame of the machine or the dot and dash disks.

While one embodiment of the invention has been disclosed, it is to be understood that the 45 inventive idea may be carried out in a number of ways. This application is therefore not to be limited to the precise details described, but is intended to cover all variations and modifications thereof falling within the scope of the 50 appended claims.

I claim:

1. A telegraph code transmitting device including a rotary member for making and breaking a circuit to form a series of dashes, a second rotary member for making and breaking a circuit to 55 form a series of dots, a driving member constantly tending to rotate both of said rotary members, stop means normally holding both of said rotary members against rotation, and manually controlled means for selectively releasing either of said rotary members for rotation under the influence of said driving member.

2. A telegraph code transmitting device including a rotary member for making and breaking a circuit to form a series of dashes, a second rotary member for making and breaking a circuit to

60 form a series of dots, a driving member constantly tending to rotate both of said rotary members, adjustable means for varying the speed of

65 said driving member, stop means normally holding both of said rotary members against rotation, and manually controlled means for selectively releasing either of said rotary members for rotation under the influence of said driving member.

3. A telegraph code transmitting device including a rotary member for making and breaking a circuit to form a series of dashes, a second rotary member for making and breaking a circuit to

70 form a series of dots, a driving member constantly tending to rotate both of said rotary members, adjustable means for varying the speed of

75 said driving member, stop means normally holding both of said rotary members against rotation, and manually controlled means for selectively releasing either of said rotary members for rotation under the influence of said driving member.

3. A telegraph code transmitting device including a rotary member for making and breaking a circuit to form a series of dashes, a second rotary member for making and breaking a circuit to form a series of dots, a driving member, a slippable frictional driving connection between said driving member and each of said rotary members to tend to rotate both of said rotary members, separate stop members normally holding each of said rotary members against rotation, and manually controlled means for selectively releasing either of said stop members to permit rotation of the rotary member associated therewith.
4. A telegraph code transmitting device including a rotary member for making and breaking a circuit to form a series of dashes, a second rotary member for making and breaking a circuit to form a series of dots, a driving member, a slippable frictional driving connection between said driving member and each of said rotary members to tend to rotate both of said rotary members, separate stop members normally holding each of said rotary members against rotation, and manually controlled means movable in one direction to release one of said stop members to permit rotation of one of the rotary members and movable in an opposite direction to release the other of said stop members to permit rotation of the other rotary member.
5. A telegraph code transmitting device including a shaft, a motor for turning said shaft, a first disk rotatably mounted on said shaft and having a dash and space forming periphery, a second disk rotatably mounted on said shaft and having a dot and space forming periphery, friction means mounted on and turning with said shaft adjacent each of said disks, spring means holding said disks in contact with said friction means so that said disks tend to turn with said shaft, and manually operable means for controlling rotation of said disks.
6. A telegraph code transmitting device including a shaft, a motor for turning said shaft, a first disk rotatably mounted on said shaft and having a dash and space forming periphery, a second disk rotatably mounted on said shaft and having a dot and space forming periphery, friction means mounted on and turning with said shaft adjacent each of said disks, spring means holding said disks in contact with said friction means so that said disks tend to turn with said shaft, a first manually operable member for controlling rotation of said first disk, and a second manually operable member for controlling rotation of said second disk.
7. A telegraph code transmitting device including a shaft, a motor for turning said shaft, a first disk rotatably mounted on said shaft and having a dash and space forming periphery, a second disk rotatably mounted on said shaft and having a dot and space forming periphery, friction means mounted on and turning with said shaft adjacent each of said disks, spring means holding said disks in contact with said friction means so that said disks tend to turn with said shaft, a first releasable latch member cooperating with said first disk to hold said disk against rotation, a second releasable latch member cooperating with said second disk to hold said disk against rotation, and manually operable parts movable in one direction to release one of said latch members and movable in an opposite direction to release the other of said latch members.
8. A telegraph code transmitting device including a shaft, a motor for turning said shaft, a first disk rotatably mounted on said shaft and having a dash and space forming periphery, a second disk rotatably mounted on said shaft and having a dot and space forming periphery, friction means mounted on and turning with said shaft adjacent each of said disks, spring means holding said disks in contact with said friction means so that said disks tend to turn with said shaft, a first releasable latch member cooperating with said first disk to hold said disk against rotation, a second releasable latch member cooperating with said second disk to hold said disk against rotation, a first manually operable member movable in one direction to release said first latch member, and a second manually operable member movable in an opposite direction to release said second latch member.
9. A construction as described in claim 8, in which said two manually operable members lie approximately side by side and in which the releasing movement of each is in a direction toward the other.
10. A telegraph code sending device including a motor, a worm driven by said motor, a friction disk driven by said worm, a second disk mounted for rotation about an axis approximately perpendicular to the axis of said friction disk, said second disk contacting with the face of said friction disk to be driven thereby, means for moving said second disk farther from or closer to the axis of rotation of said friction disk to vary the speed of rotation of said second disk relative to the speed of the friction disk, dot sending means driven from said second disk, dash sending means also driven from said second disk, and manually operable means for separately controlling said dot sending means and said dash sending means.

WALTER RAYMOND STARKINS.
